POCKET STRUCTURE FOR NURSES' UNIFORMS AND OTHER GARMENTS

Emanuel Kotkes, Rockville Centre, N. Y.

Application November 23, 1951, Serial No. 257,719

8 Claims. (Cl. 2—253)

1

This invention relates to new and useful improvements in a pocket structure for attachment to a nurses' uniform.

More specifically, the present invention proposes the construction of an improved pocket structure of the type disclosed which is constructed to include a main outer wall which when secured to the front of the uniform combines with the material of the uniform to provide a large main pocket for receiving pads, papers, handkerchiefs and similar articles and which has vertically extended minor pockets along its side edges for pens, scissors and similar elongated articles common to the nursing profession.

Still further, the present invention proposes the provision of an inner wall which is co-extensive with the main outer wall at the top thereof and positioned to the rear of the minor pockets to function as a guide and for retaining articles placed within the large main pocket from slipping into position between the main outer wall and the minor pockets.

As a further object, the present invention proposes constructing a pocket structure of the type disclosed which is fashioned of six pieces joined together in such a manner that none of the joining stitches are visible from the outside of the pocket structure with the exception of those stitches which mount the main outer wall in position on the uniform.

Another object of the present invention proposes arranging the minor pockets to have mouth openings above the top edge of the main outer wall backed by upward extensions of their rear walls and the rear wall which is co-extensive with the top portion of the main outer wall to guide the articles being inserted into the minor pockets.

It is a further object of the present invention to construct a pocket structure which is simple and durable, which can be quickly and easily mounted in position on a nurse's uniform and which can be manufactured and sold at a reasonable cost.

For further comprehension of the invention, and of the objects and advantages thereof, reference will be had to the following description and accompanying drawing, and to the appended claims in which the various novel features of the invention are more particularly set forth.

On the accompanying drawings forming a material part of the present inclosure:

Fig. 12 is a developed view of the rear wall of the minor pocket which receives the scissors or the like.

Fig. 13 is a developed view of the inner wall, per se.

Fig. 14 is a developed view showing one of the preliminary steps in the assembly of the pocket structure.

Fig. 15 is a developed view showing a further step in the assembly of the pocket structure.

The pocket structure, according to the present invention, is constructed entirely of cloth material and is to be stitched to the front of a nurse's uniform 20 at the usual location for a pocket. On the drawings, the uniform is only fragmentarily shown.

The pocket structure is constructed to include a main outer wall 21 which is shaped, as best shown in Fig. 8, to have its top corners cut off diagonally to provide downwardly and outwardly sloped top edge portions 22 and 23. Between the inner ends of the downwardly and outwardly sloped top edge portions 22 and 23, the main outer wall 21 has a reentrantly arranged V-shaped top edge portion 24. The side edges 25 and 26 of the main outer wall 21 are sloped or

Fig. 1 is a perspective view of the pocket struc-

converged downward to a flat horizontal bottom edge 27.

When the pocket structure is stitched to the uniform 20, as will be hereinafter described, the main outer wall 21 combines with the material of the uniform to provide a large main pocket 28 to receive a note pad, handkerchief and similar articles. In Fig. 1, a note pad 29 is shown in position within the main large pocket 28.

Extended vertically along the side edges 25 and 26 of the main outer wall 21, there are minor pockets 30 and 31. The minor pocket 30 is provided for receiving a fountain pen 32 and the minor pocket is provided for receiving a pair of scissors 33, see Fig. 1.

Located behind the minor pockets 30 and 31 and co-extensive with the top portion of the main outer wall 21, there is an inner wall 34, the shape of which is best shown in Fig. 13. The inner wall 34 is conformed to the shape of the top portion of the main outer wall 21 except that the top corners of the inner wall are not cut away. Thus, the inner wall 34 has a reentrantly extended V-shaped top edge 35 matching the formation of the V-shaped top edge portion 24 of the main outer wall. The ends of the V-shaped top edge 35 continue into downwardly converged side edges 36 and 37 matching the convergence of the side edges 25 and 26 of the main outer wall 21. The inner wall 34 has a straight bottom edge 38 spaced some distance above the bottom edge 27 of the main outer wall 21. The bottom edge 38 of the inner wall 34 can be finished with a seam to prevent unravelling, if desired.

When the inner wall 34 is properly positioned behind the main outer wall 21, the top corners of the inner wall will extend upward above the downwardly and outwardly sloped top edge portions 22 and 23 of the main outer wall. For guiding proper aligning of the walls 21 and 34, the side edges 25 and 26 of the main outer wall 21 are formed with notches 25^a and 26^a which are to be aligned with complementary notches 36^a and 37^a formed in the vertical side edges 36 and 37 of the inner wall 34.

The minor pocket 30 for the fountain pen 32 is constructed of a front wall 39 and a rear wall 40. The front wall 39 and the rear wall 40 are alike in configuration except for the formation of their top edges. The front wall 39 has a top edge 41 matching the formation of the downwardly and outwardly sloped top edge portion 22 and the adjacent end of the V-shaped top edge portion 24 of the main outer wall 21. The rear wall 40 has a top edge 42 which is sloped downward and inward matching the slope of the adjacent end of the V-shaped top edge 35 of the inner wall 34. The outer ends of the top edges 41 and 42 of the walls 39 and 40 continue into downwardly and inwardly sloped outer side edges 43 and 44 matching the slope of the adjacent side edges 25 and 36 of the walls 21 and 34. The outer side edges 43 and 44 are formed with notches 43^a and 44^a, respectively, for insuring the proper alignment of the walls 39 and 40 and the proper alignment of the minor pocket 30 with the walls 21 and 34.

The walls 39 and 40 of the minor pocket 30 have straight inner side edges 45 and 46 and straight horizontal bottom edges 47 and 48. The straight inner side edges 45 and 46 and the straight horizontal bottom edges 47 and 48 of the front and rear walls of the minor pocket 30 are secured together by a line of stitches 49. From Figs. 1, 2 and 15, it will be noted that when the minor pocket 30 is mounted in position, the walls 39 and

40 thereof are longer than the inner wall 34 but shorter than the main outer wall 21.

The minor pocket 30 which receives the scissors 33 is also constructed of a front wall 50 and a rear wall 51, the shapes of which are best shown in Figs. 11 and 12. The walls 50 and 51 are of different lengths. The front wall 50 has a top edge 52 cut to match the formation of the downwardly and outwardly sloped top edge portion 23 and the adjacent end of the V-shaped top edge portion 24 of the front wall 21. At its outer or low end, the top edge 52 continues into a downwardly and inwardly sloped outer side edge 53 which matches the slope of the outer side edge 26 of the main front wall 21. At its inner end, the top edge 52 of the front wall 50 continues into a straight inner side edge 54. The bottom ends of the side edges 53 and 54 are joined by a straight horizontal bottom edge 55. From Fig. 15, it will be noted that the front wall 50 of the minor pocket 30 is just slightly longer than the walls 39 and 40.

The rear wall 51 of the minor pocket 33 is of a length corresponding to the length of the main outer wall 21. That rear wall 51 has a downwardly and inwardly sloped top edge 56 matching the slope of the adjacent end of the V-shaped top edge 35 of the inner wall 34. At its high or outer end, the top edge 56 continues into an inwardly sloped outer side edge 57 which matches the inclination of the outer side edge 26 of the main outer wall 21, the outer side edge 37 of the inner wall 34 and the outer side edge 53 of the front wall 50 of the minor pocket 33. At its low or inner end, the top edge 56 continues into a straight inner side edge 58 complementary to the inner side edge 54 of the front wall 50. Extended outward from the inner side edge 58, there is a straight horizontal bottom edge portion 59 complementary to the straight bottom edge 27 of the main outer wall 21. The outer side edge 57 and the horizontal bottom edge portion 59 are joined by an inclined bottom edge portion 60 arranged at an inclination to the horizontal bottom edge portion 59.

To insure proper matching of the front wall 50 and the rear wall 51 to form the minor pocket 33, the outer side edges 53 and 57 of those walls are formed respectively with notches 53^a and 57^a. With the notches 53^a and 57^a aligned, the inner side edge 54 of the front wall 50 and the aligned portion of the inner side edge 58 of the rear wall 51 are joined by a vertically extended line of stitches 61.

To understand the manner of assembling the six pieces just described to form the pocket structure of the present invention, reference will now be had to Figs. 14 and 15. To start the assembly, the main outer wall 21 is first rested down on a flat surface with its outer face facing upward. Next, the front wall 39 of the minor pocket 30 is rested on the main outer wall 21 with its outer side edge 43 flush with the side edge 25 of the main outer wall and with the notches 43^a and 25^a in alignment. The top edge 41 of the front wall 39 is then stitched to the downwardly and outwardly sloped top edge portion 22 and the adjacent end of the V-shaped top edge portion 24 of the main outer wall 21 by a line of stitches 62. Then the front wall 50 of the minor pocket 30 is placed on the main outer wall 21 with its outer side edge 53 flush with the side edge 26 of the main outer wall 21 and with the notches 53^a and 26^a in alignment. The top edge 52 of the front wall 50 is then secured to the downwardly and

outwardly sloped top edge portion 23 and the adjacent end of the V-shaped top edge portion 24 of the main outer wall 21 by a line of stitches 63. The main outer wall 21 and the front walls 39 and 50, will then appear as shown in Fig. 14.

The walls 39 and 50 are then swung over the top of the main outer wall 21 to depend along the inner face thereof and to cause the seams formed by the lines of stitches to come between the adjacent faces of the wall 21 and the walls 39 and 50, see Figs. 3 and 4.

The next step in assembly is to lay the main outer wall 21 down flat so that the walls 39 and 50 are exposed uppermost. Then the rear wall 40 of the minor pocket 30 is positioned on the front wall 39 of that minor pocket so that the notches 43^a and 44^a of the outer side edges 43 and 44 are aligned, see Fig. 15. The inner side edges 45 and 46 and the bottom edges 47 and 48 are then joined by the line of stitches 49. Similarly, the rear wall 51 of the minor pocket 31 is positioned on the front wall 50 thereof with the notches 53^a and 57^a of the outer side edges 53 and 57 in perfect alignment. The inner side edge 54 of the front wall 50 and the adjacent portion of the inner side edge 58 of the rear wall 51 are then joined by the line of stitches 61, again, see Fig. 15.

When the rear walls 40 and 51 are joined to the respective front walls 39 and 50, the assembly of the pocket structure is then completed by laying the inner wall 34 on a flat surface with its outer face faced downward. The main outer wall 21 with the attached minor pockets 30 and 31 is then positioned on top of the inner wall 34 with the outer face of the main outer wall facing downward and resting on the inner wall and with the minor pockets 30 and 31 on top of the main outer wall, as shown in Fig. 15. At the one side, the notches 36^a, 25^a, 43^a and 44^a are brought into perfect alignment and at the other side, the notches 37^a, 26^a, 53^a and 57^a are brought into perfect alignment. The parts are then joined together by one continuous line of stitches 64 which extends from the top end of the inclined bottom edge portion 60 of the rear wall 51 of the minor pocket 31 upward along the right side of the structure, as viewed in Fig. 15, completely across the top thereof and then downward along the left side to the stitches 49 along the bottom end of the minor pocket 30. In extending across the top of the structure, it will be noted that the stitches 64 follow the V-shaped top edge portion 35 of the inner wall 34 and the aligned top edges 42 and 56 of the rear walls 40 and 51, respectively, of the minor pockets 30 and 31. Following the stitching 64, the inner wall 34 is then swung over the top of the main front wall 21 to depend downward along the rear faces of the rear walls 40 and 51 of the minor pockets 30 and 31, see Fig. 2 where the assembled pocket structure is illustrated as viewed from the rear and prior to attachment to the uniform 20.

To mount the pocket structure on the uniform 20, the side edges thereof beneath the bottom edge 33 of the inner wall 34 are bent inward along the lines 65 and 66 and the bottom edge 27 of the outer wall 21 and the bottom edge portion 59 of the rear wall 51 of the minor pocket 31 are bent upward along the line 67, see Fig. 2. The pocket structure is then positioned against the uniform 20 at the desired location and stitched in position by a continuous line of stitches 68 extended completely along the outer side edges and the bottom edge of the pocket structure.

From Fig. 4 it will be noted that the line of stitches 68 where they extend along the bottom of the pocket structure also secure the bottom edge portion 59 of the rear wall 51 of the minor pocket 31 in position. The inclined bottom edge portion 60 is provided to relieve the bulkiness of the material in the lower left-hand corner of the pocket structure as viewed in Fig. 1. The minor pocket 30 is closed completely along its inner and bottom edges and is positioned on the pocket structure so that the top end of the fountain pen 32 inserted thereinto will project slightly from the top of that minor pocket so that a grip may be had thereon for removing the pen when desired. On the other hand, the minor pocket 31 opens to the interior of the main large pocket 28 below the bottom edge 55 of the front wall 50 of that pocket and along the bottom portion of the inner side edge 58 of that pocket and below the line of stitches 61. That opening is provided so that curved tip ends of certain surgical scissors can be projected into the large main pocket 28 at the bottom of the minor pocket 31 thus accommodating such scissors without undue strain on the seams of the minor pocket 31.

Referring to the left side of Figs. 1 and 4, it will be noted that stitches 68^a are extended inward from the adjacent top end of the line of stitches 68 securing the top edge 56 of the rear wall 51 of the minor pocket 31 and the adjacent end portion of the V-shaped top edge 35 of the inner wall 34 to the uniform 20. Those stitches 68^a extend inward to the junction of the downwardly and outwardly sloped top edge portion 23 with the adjacent end of the V-shaped top edge portion 24 of the front wall 21. While the stitches 68^a reduce the width of the mouth opening to the large main pocket 28 they do provide additional support for the minor pocket 31 which must carry the heavy surgical scissors.

From the foregoing description, it will be apparent that the present invention proposes a novel pocket structure for attachment to nurses' uniforms comprised of six simple cloth pieces and joined together and to the uniform in such a way that no stitches show with the exception of those which mount the pocket structure in position on the uniform. While the pocket structure of the present invention is intended primarily for use on nurses' uniforms it is appreciated that changes and modifications are possible, all within the scope and intent of the present invention, which would adapt the pocket structure to uniforms worn by persons engaged in other occupations.

While I have illustrated and described the preferred embodiment of my invention, it is to be understood that I do not limit myself to the precise construction herein disclosed and the right is reserved to all changes and modifications coming within the scope of the invention as set forth in the appended claims.

Having thus described my invention, what I claim as new and desire to secure by United States Letters Patent is:

1. A pocket structure for attachment to the front of a nurse's uniform or the like, comprising a main outer wall for attachment along its side and bottom edges to the front of the uniform to form a main pocket, said main outer wall being shaped so as to have a straight, horizontal bottom edge, a pair of substantially straight side edges extending downward to said bottom edge, and a top edge, said main outer wall having its top corners cut off diagonally whereby to provide downwardly and outwardly sloped top edge por-

tions adjacent said top edge, an inner wall, said inner wall being coextensive with the upper portion of said outer wall and having a substantially straight horizontal bottom edge, a pair of substantially straight side edges extending downward to said bottom edge, said side edges of said inner wall being substantially less in length than said side edges of said outer wall and adapted to coincide therewith, and a top edge, said top edge being adapted to coincide with said top edge of said outer wall, the upper corners of said inner wall extending upwardly and outwardly beyond said cut-off corners of said outer wall, said inner wall being seamed to said outer wall along the top edges of said outer and inner walls intermediate said cut-off corners of said outer wall, and spaced minor pockets extended vertically along the sides of said outer wall intermediate said inner and outer walls, said minor pockets having rear and front walls secured along their outer edges to the side edges of said inner and outer walls, said front walls of said minor pockets having their top edges cut off diagonally and adapted to coincide with said cut-off corners of said outer wall and secured thereto, said rear walls of said minor pockets having their top edges shaped so as to coincide with the upper corners of said inner wall and secured thereto above said cut-off corners of said outer wall.

2. A pocket structure for attachment to the front of a nurse's uniform or the like, comprising a main outer wall for attachment along its side and bottom edges to the front of the uniform to form a main pocket, said main outer wall being shaped so as to have a straight, horizontal bottom edge, a pair of substantially straight side edges extending downward to said bottom edge, and a top edge, said main outer wall having its top corners cut off diagonally whereby to provide downwardly and outwardly sloped top edge portions adjacent said top edge, an inner wall, said inner wall being coextensive with the upper portion of said outer wall and having a substantially straight horizontal bottom edge, a pair of substantially straight side edges extending downward to said bottom edge, said side edges of said inner wall being substantially less in length than said side edges of said outer wall and adapted to coincide therewith, and a top edge, said top edge being adapted to coincide with said top edge of said outer wall, the upper corners of said inner wall extending upwardly and outwardly beyond said cut-off corners of said outer wall, said inner wall being seamed to said outer wall along the top edges of said outer and inner walls intermediate said cut-off corners of said outer wall, and spaced minor pockets extended vertically along the sides of said outer wall intermediate said inner and outer walls, said minor pockets having rear and front walls secured along their outer edges to the side edges of said inner and outer walls, said front walls of said minor pockets having their top edges cut off diagonally and adapted to coincide with said cut-off corners of said outer wall and secured thereto, said rear walls of said minor pockets having their top edges shaped so as to coincide with the upper corners of said inner wall and secured thereto above said cut-off corners of said outer wall, said top edge of said outer wall being substantially V-shaped inwardly intermediate the cut-off corners thereof, said top edge of said inner wall being substantially V-shaped inwardly adapted to coincide with said V-shaped top edge of said outer wall.

3. A pocket structure for attachment to the

front of a nurse's uniform or the like, comprising a main outer wall for attachment along its side and bottom edges to the front of the uniform to form a main pocket, said main outer wall being shaped so as to have a straight, horizontal bottom edge, a pair of substantially straight side edges extending downward to said bottom edge, and a top edge, said main outer wall having its top corners cut off diagonally whereby to provide downwardly and outwardly sloped top edge portions adjacent said top edge, an inner wall, said inner wall being coextensive with the upper portion of said outer wall and having a substantially straight horizontal bottom edge, a pair of substantially straight side edges extending downward to said bottom edge, said side edges of said inner wall being substantially less in length than said side edges of said outer wall and adapted to coincide therewith, and a top edge, said top edge being adapted to coincide with said top edge of said outer wall, the upper corners of said inner wall extending upwardly and outwardly beyond said cut-off corners of said outer wall, said inner wall being seamed to said outer wall along the top edges of said outer and inner walls intermediate said cut-off corners of said outer wall, and spaced minor pockets extended vertically along the sides of said outer wall intermediate said inner and outer walls, said minor pockets having rear and front walls secured along their outer edges to the side edges of said inner and outer walls, said front walls of said minor pockets having their top edges cut off diagonally and adapted to coincide with said cut-off corners of said outer wall and secured thereto, said rear walls of said minor pockets having their top edges shaped so as to coincide with the upper corners of said inner wall and secured thereto above said cut-off corners of said outer wall, said top edge of said outer wall being substantially V-shaped inwardly intermediate the cut-off corners thereof, said top edge of said inner wall being substantially V-shaped inwardly adapted to coincide with said V-shaped top edge of said outer wall, said front and rear walls of one of said minor pockets having flush inner side edges and flush bottom edges, said flush side and bottom edges being joined together by lines of stitches adapting that minor pocket to receive a fountain pen.

4. A pocket structure for attachment to the front of a nurse's uniform or the like, comprising a main outer wall for attachment along its side and bottom edges to the front of the uniform to form a main pocket, said main outer wall being shaped so as to have a straight horizontal bottom edge, a pair of substantially straight side edges extending downward to said bottom edge, and a top edge, said main outer wall having its top corners cut off diagonally whereby to provide downwardly and outwardly sloped top edge portions adjacent said top edge, an inner wall, said inner wall being coextensive with the upper portion of said outer wall and having a substantially straight horizontal bottom edge, a pair of substantially straight side edges extending downward to said bottom edge, said side edges of said inner wall being substantially less in length than said side edges of said outer wall and adapted to coincide therewith, and a top edge, said top edge being adapted to coincide with said top edge of said outer wall, the upper corners of said inner wall extending upwardly and outwardly beyond said cut-off corners of said outer wall, said inner wall being seamed to said

outer wall along the top edges of said outer and inner walls intermediate said cut-off corners of said outer wall, and spaced minor pockets extended vertically along the sides of said outer wall intermediate said inner and outer walls, said minor pockets having rear and front walls secured along their outer edges to the side edges of said inner and outer walls, said front walls of said minor pockets having their top edges cut off diagonally and adapted to coincide with said cut-off corners of said outer wall and secured thereto, said rear walls of said minor pockets having their top edges shaped so as to coincide with the upper corners of said inner wall and secured thereto above said cut-off corners of said outer wall, said top edge of said outer wall being substantially V-shaped inwardly intermediate the cut-off corners thereof, said top edge of said inner wall being substantially V-shaped inwardly adapted to coincide with said V-shaped top edge of said outer wall, said front and rear walls of one of said minor pockets having flush inner side edges and flush bottom edges, said flush side and bottom edges being joined together by lines of stitches adapting that minor pocket to receive a fountain pen, said front and rear walls of the other of said minor pockets being of different lengths with the rear wall longer than the front wall and having flush inner side edges, stitches joining the inner side edge of the shorter front wall to the adjacent portion of the inner side edge of the respective rear wall leaving the bottom of that other minor pocket open to accommodate surgical scissors having bent tip ends, the said rear wall of the said other minor pocket being extended the full height of said main outer wall and having its bottom end anchored in position by the means which attaches the main outer wall to the uniform.

5. A pocket structure for attachment to the front of a nurse's uniform or the like, comprising a main outer wall for attachment along its side and bottom edges to the front of the uniform to form a main pocket, said main outer wall being shaped so as to have a straight horizontal bottom edge, a pair of substantially straight side edges extending downward to said bottom edge, and a top edge, said main outer wall having its top corners cut off diagonally whereby to provide downwardly and outwardly sloped top edge portions adjacent said top edge, an inner wall, said inner wall being coextensive with the upper portion of said outer wall and having a substantially straight horizontal bottom edge, a pair of substantially straight side edges extending downward to said bottom edge, said side edges of said inner wall being substantially less in length than said side edges of said outer wall and adapted to coincide therewith, and a top edge, said top edge being adapted to coincide with said top edge of said outer wall, the upper corners of said inner wall extending upwardly and outwardly beyond said cut-off corners of said outer wall, said inner wall being seamed to said outer wall along the top edges of said outer and inner walls intermediate said cut-off corners of said outer wall, and spaced minor pockets extended vertically along the sides of said outer wall intermediate said inner and outer walls, said minor pockets having rear and front walls secured along their outer edges to the side edges of said inner and outer walls, said front walls of said minor pockets having their top edges cut off diagonally and adapted to coincide with said cut-off corners of said outer wall and secured thereto, said rear walls of said minor pockets having their top edges shaped so as to coincide with the upper corners of said inner wall and secured thereto above said cut-off corners of said outer wall, said top edge of said outer wall being substantially V-shaped inwardly intermediate the cut-off corners thereof, said top edge of said inner wall being substantially V-shaped inwardly adapted to coincide with said V-shaped top edge of said outer wall, said front and rear walls of one of said minor pockets having flush inner side edges and flush bottom edges, said flush side and bottom edges being joined together by lines of stitches adapting that minor pocket to receive a fountain pen, said front and rear walls of the other of said minor pockets being of different lengths with the rear wall longer than the front wall and having flush inner side

inwardly intermediate the cut-off corners thereof, said top edge of said inner wall being substantially V-shaped inwardly adapted to coincide with said V-shaped top edge of said outer wall, said front and rear walls of one of said minor pockets having flush inner side edges and flush bottom edges, said flush side and bottom edges being joined together by lines of stitches adapting that minor pocket to receive a fountain pen, said front and rear walls of the other of said minor pockets being of different lengths with the rear wall longer than the front wall and having flush inner side edges, stitches joining the inner side edge of the shorter front wall to the adjacent portion of the inner side edge of the respective rear wall leaving the bottom of that other minor pocket open to accommodate surgical scissors having bent tip ends, the said rear wall of the said other minor pocket being extended the full height of said main outer wall and having its bottom end anchored in position by the means which attaches the main outer wall to the uniform.

6. A pocket structure for attachment to the front of a nurse's uniform or the like, comprising a main outer wall for attachment along its side and bottom edges to the front of the uniform to form a main pocket, said main outer wall being shaped so as to have a straight horizontal bottom edge, a pair of substantially straight side edges extending downward to said bottom edge, and a top edge, said main outer wall having its top corners cut off diagonally whereby to provide downwardly and outwardly sloped top edge portions adjacent said top edge, an inner wall, said inner wall being coextensive with the upper portion of said outer wall and having a substantially straight horizontal bottom edge, a pair of substantially straight side edges extending downward to said bottom edge, said side edges of said inner wall being substantially less in length than said side edges of said outer wall and adapted to coincide therewith, and a top edge, said top edge being adapted to coincide with said top edge of said outer wall, the upper corners of said inner wall extending upwardly and outwardly beyond said cut-off corners of said outer wall, said inner wall being seamed to said outer wall along the top edges of said outer and inner walls intermediate said cut-off corners of said outer wall, and spaced minor pockets extended vertically along the sides of said outer wall intermediate said inner and outer walls, said minor pockets having rear and front walls secured along their outer edges to the side edges of said inner and outer walls, said front walls of said minor pockets having their top edges cut off diagonally and adapted to coincide with said cut-off corners of said outer wall and secured thereto, said rear walls of said minor pockets having their top edges shaped so as to coincide with the upper corners of said inner wall and secured thereto above said cut-off corners of said outer wall, said top edge of said outer wall being substantially V-shaped inwardly intermediate the cut-off corners thereof, said top edge of said inner wall being substantially V-shaped inwardly adapted to coincide with said V-shaped top edge of said outer wall, said front and rear walls of one of said minor pockets having flush inner side edges and flush bottom edges, said flush side and bottom edges being joined together by lines of stitches adapting that minor pocket to receive a fountain pen, said front and rear walls of the other of said minor pockets being of different lengths with the rear wall longer than the front wall and having flush inner side

edges, stitches joining the inner side edge of the shorter front wall to the adjacent portion of the inner side edge of the respective rear wall leaving the bottom of that other minor pocket open to accommodate surgical scissors having bent tip ends, the said rear wall of the said other minor pocket being extended the full height of said main outer wall and having its bottom end anchored in position by the means which attaches the main outer wall to the uniform, the said rear wall of the said other minor pocket having an inclined bottom edge portion facing the adjacent bottom corner of the pocket structure to reduce bulkiness in that bottom corner when the pocket structure is attached to the uniform.

7. A pocket structure for attachment to the front of a nurse's uniform or the like, comprising a main outer wall for attachment along its side and bottom edges to the front of the uniform to form a main pocket, said main outer wall being shaped so as to have a straight horizontal bottom edge, a pair of substantially straight side edges extending downward to said bottom edge, and a top edge, said main outer wall having its top corners cut off diagonally whereby to provide downwardly and outwardly sloped top edge portions adjacent said top edge, an inner wall, said inner wall being coextensive with the upper portion of said outer wall and having a substantially straight horizontal bottom edge, a pair of substantially straight side edges extending downward to said bottom edge, said side edges of said inner wall being substantially less in length than said side edges of said outer wall and adapted to coincide therewith, and a top edge, said top edge being adapted to coincide with said top edge of said outer wall, the upper corners of said inner wall extending upwardly and outwardly beyond said cut-off corners of said outer wall, said inner wall being seamed to said outer wall along the top edges of said outer and inner walls intermediate said cut-off corners of said outer wall, and spaced minor pockets extended vertically along the sides of said outer wall intermediate said inner and outer walls, said minor pockets having rear and front walls secured along their outer edges to the side edges of said inner and outer walls, said front walls of said minor pockets having their top edges cut off diagonally and adapted to coincide with said cut-off corners of said outer wall and secured thereto, said rear walls of said minor pockets having their top edges shaped so as to coincide with the upper corners of said inner wall and secured thereto above said cut-off corners of said outer wall, said top edge of said outer wall being substantially V-shaped inwardly intermediate the cut-off corners thereof, said top edge of said inner wall being substantially V-shaped inwardly adapted to coincide with said V-shaped top edge of said outer wall, said front and rear walls of one of said minor pockets having flush inner side edges and flush bottom edges, said flush side and bottom edges being joined together by lines of stitches adapting that minor pocket to receive a fountain pen, said front and rear walls of the other of said minor pockets being of different lengths with the rear wall longer than the front wall and having flush inner side edges, stitches joining the inner side edge of the shorter front wall to the adjacent portion of the inner side edge of the respective rear wall leaving the bottom of that other minor pocket open to accommodate surgical scissors having bent tip ends, the said rear wall of the said other minor pocket being

extended the full height of said main outer wall and having its bottom end anchored in position by the means which attaches the main outer wall to the uniform, the said rear wall of the said other minor pocket having an inclined bottom edge portion facing the adjacent bottom corner of the pocket structure to reduce bulkiness in that bottom corner when the pocket structure is attached to the uniform, and line of stitches securing the side and bottom edges of the pocket structure to the nurse's uniform.

8. A pocket structure for attachment to the front of a nurse's uniform or the like, comprising a main outer wall for attachment along its side and bottom edges to the front of the uniform to form a main pocket, said main outer wall being shaped so as to have a straight horizontal bottom edge, a pair of substantially straight side edges extending downward to said bottom edge, and a top edge, said main outer wall having its top corners cut off diagonally whereby to provide downwardly and outwardly sloped top edge portions adjacent said top edge, an inner wall, said inner wall being coextensive with the upper portion of said outer wall and having a substantially straight horizontal bottom edge, a pair of substantially straight side edges extending downward to said bottom edge, said side edges of said inner wall being substantially less in length than said side edges of said outer wall and adapted to coincide therewith, and a top edge, said top edge being adapted to coincide with said top edge of said outer wall, the upper corners of said inner wall extending upwardly and outwardly beyond said cut-off corners of said outer wall, said inner wall being seamed to said outer wall along the top edges of said outer and inner walls intermediate said cut-off corners of said outer wall, and spaced minor pockets extended vertically along the sides of said outer wall intermediate said inner and outer walls, said minor pockets having rear and front walls secured along their outer edges to the side edges of said inner and outer walls, said front walls of said minor pockets having their top edges cut off diagonally and adapted to coincide with said cut-off corners of said outer wall and secured thereto, said rear walls of said minor pockets having their top edges shaped so as to coincide with the upper corners of said inner wall and secured thereto above said cut-off corners of said outer wall, said top edge of said outer wall being substantially V-shaped inwardly intermediate the cut-off corners thereof, said top edge of said inner wall being substantially V-shaped inwardly adapted to coincide with said V-shaped top edge of said outer wall, said front and rear walls of one of said minor pockets having flush inner side edges and flush bottom edges, said flush side and bottom edges being joined together by lines of stitches adapting that minor pocket to receive a fountain pen, said front and rear walls of the other of said minor pockets being of different lengths with the rear wall longer than the front wall and having flush inner side edges, stitches joining the inner edge of the shorter front wall to the adjacent portion of the inner side edge of the respective rear wall leaving the bottom of that other minor pocket open to accommodate surgical scissors having bent tip ends, the said rear wall of the said other minor pocket being extended the full height of said main outer wall and having its bottom end anchored in position by the means which attaches the main outer wall to the uniform, the said rear wall of the said other minor pocket

13

having an inclined bottom edge portion facing the adjacent bottom corner of the pocket structure to reduce bulkiness in that bottom corner when the pocket structure is attached to the uniform, and line of stitches securing the side and bottom edges of the pocket structure to the nurse's uniform, said latter lines of stitches being extended inward over the top of the said other minor pocket which receives the scissors providing additional support for that pocket.

EMANUEL KOTKES.
